United States Patent Office

Des. 228,924
Patented Oct. 30, 1973

228,924

FENCE SECTION

Leo P. Niemiec, 5627 Emerson,
Morton Grove, Ill. 60053

Filed Dec. 29, 1971, Ser. No. 213,789

Term of patent 14 years

Int. Cl. D25—99

U.S. Cl. D28—1 A

FIG. 3

FIG. 4

FIG. 5

FIG. 6

FIG. 1 is a front view of a fence section showing my new design;

FIG. 2 is a back view thereof;

FIG. 3 is a cross-sectional view taken substantially along the line 3—3 of FIG. 1;

FIG. 4 is a cross-sectional view taken substantially along the line 4—4 of FIG. 1;

FIG. 5 is a cross-sectional view taken substantially along the line 5—5 of FIG. 1; and

FIG. 6 is a cross-sectional view taken substantially along the line 6—6 of FIG. 1.

What is claimed:

The ornamental design for a fence section, substantially as shown.
